METHOD AND REFRIGERATING APPARATUS FOR THE COLD STORAGE OF GOODS

Ernest Edmund Larkin, Pinner, England, assignor
to The Union Cold Storage Company Limited,
London, England, a British company

Application March 9, 1945, Serial No. 581,764
In Great Britain March 9, 1944

5 Claims. (Cl. 62—102)

1

This invention relates to methods and refrigerating apparatus for the cold storage of food and other goods, which apparatus is of the type (hereinafter referred to as the type described) comprising an outer casing having thermally insulated walls, and an inner chamber supported therein for accommodating the goods to be stored, a cooling space surrounding the inner chamber being arranged within the outer casing.

In one construction of apparatus of the type described proposed heretofore, the outer casing had an inlet in one side wall above the bottom, and an outlet in the top wall for circulating cold compressed air from the exhaust pipe of a compressed-air motor through the cooling space which might be provided with baffles or partitions for prolonging the circulation of the cold air around the inner chamber, which construction had the drawback that the air in the cooling space was constantly changed, and the refrigerating action was dependent on the running of the motor.

In another construction, intended particularly for the cold storage of eggs in a tank constituting the inner chamber, provision was made for supplying a neutral gas, such as carbon dioxide, to the tank after it had been charged with eggs, and then circulating cold air in the cooling space extending around the top, bottom and two ends of the tank by means of a fan and a cooling device, such as an evaporator coil of a refrigerating plant, situated in the cooling space; this construction had the drawback that two sides of the inner chamber were in close contact with the outer casing, so that heat could leak through to the inner chamber, and every time the tank was emptied and recharged, the air in the cooling space was changed and replaced by warmer air, and the cooling device was liable to become frosted when restarting the circulation in the cooling space.

The present invention has for one of its objects to obviate these drawbacks, and to provide an improved construction of refrigerating and cold storage apparatus of the type described which shall have a greater thermal efficiency than those used heretofore.

Another object is to absorb the heat that tends to leak through the insulated walls of the outer casing before it is able to enter the inner chamber, and at the same time to cool the air in the inner chamber and goods stored therein to the required temperature, and when cooled to that temperature to maintain it without further change and so retard dehydration of the goods stored in the chamber.

A further object is to provide an improved construction of refrigerating and cold storage apparatus of the type described, in which the necessity of de-frosting the cooling device from

time to time after unloading and recharging the inner chamber with goods is obviated.

According to the invention there is provided a method of refrigeration comprising the steps of 5 circulating cooling air in a cooling space extending around an inner cold-storage chamber within an outer casing, and maintaining the same cooling air in the cooling space when opening and closing the inner chamber for loading and 10 unloading purposes which method is characterised by circulating the cooling air over substantially the entire area of each of the top, bottom, side and end walls of the inner chamber.

The invention also provides refrigerating and 15 cold storage apparatus of the type described, 20 wherein the cooling space is sealed, and wherein an air-tight cooling device and air-circulating means are arranged in the sealed cooling space for circulating cold air therein, and provision is 25 made for stowing goods in, and removing them from, the inner chamber without placing the sealed cooling space into open communication with the atmosphere or with any other space. Consequently, air in the cooling space can remain 30 unchanged for very long periods so that the efficiency of the apparatus is increased and there is no need periodically to de-frost the cooling device.

Conveniently a passageway for use in loading 35 and unloading the inner chamber extends air-tight through the cooling space to the inner chamber and is provided with closure means, such as a door or doors.

When the apparatus comprises a rectangular 40 outer casing and a rectangular jacketed inner chamber therein, and a plurality of partitions are arranged in the jacket to form a circuitous path for cold air in the cooling space, the partitions may be so arranged that the air flows 45 in counter current in each of the several parts of the closed cooling space situated respectively at the top wall, bottom wall, side walls and end walls of the jacket.

The invention is diagrammatically illustrated 45 by way of example in the accompanying drawings, wherein:

Figure 1 is a diagrammatic perspective view 50 showing one construction of a double-walled inner chamber, shown broken away, provided in refrigerating and cold storage apparatus according to the invention.

Figure 2 is a detail vertical section taken 55 through the lower part of the inner chamber shown in Figure 1 and the adjacent part of an outer casing drawn to a scale larger than that of Figure 1, and

Figure 3 is a perspective view of the apparatus on a scale smaller than that of Figure 1.

Like reference characters designate like parts 60 in all the views.

Referring to the drawings, refrigerating and cold storage apparatus of the type described comprises an outer casing 10 insulated within against the admission of heat by a layer of heat-insulating material 12 applied to its inner faces. A jacked or double-walled inner chamber, designated generally 14, for the cold storage of food and other articles is supported in any convenient manner within the outer casing, the relative sizes of the lined outer casing and the double-walled inner chamber 14 being such that an air space 16 for "dead" air is left between the two. As shown in Figure 2, the chamber 14 rests on spaced bearer members 18, preferably composed of wood or other material which is a poor conductor of heat.

As illustrated, the inner chamber 14 is rectangular as viewed in plan, side elevation and end elevation, and comprises an inner shell or casing 20 and an outer shell or jacket 22 spaced away therefrom to provide between the two a cooling space 24 for the circulation of cold air through it, as described hereinafter, which cooling space constitutes a hermetically sealed air space and surrounds the top, bottom, sides and ends of the inner shell 20. The walls of both shells may be flat, as shown, or corrugated. In order to enable goods to be stowed in, and removed from the inner chamber 14 without placing the jacket cooling space 24 into open communication with the atmosphere, a passageway 26 for use in loading and unloading the chamber 14 extends air-tight through the closed cooling space 24 to the inner shell 20, and is provided with closure means, such as a door 28, at its outer end. Provision is made so that the part of the outer casing adjacent to the passageway 26 affords access to the door 28 for opening and closing it. As shown the outer casing has a door 29 for this purpose.

An air-tight cooling device 30 in the form of a coil through which a refrigerant, such as brine, can be circulated is accommodated in the cooling space 24 at the lower portion of one end thereof. This coil has an inlet pipe 32 and an outlet pipe 34 which extend through the outer casing 10. Air-circulating means is also arranged in the closed cooling space 24 preferably adjacent to the cooling device. As illustrated, this air-circulating means is constituted by an electrically driven fan 36 of any convenient or known construction that is situated above the cooling coil 30, and has current-supply leads 39 extending through the outer casing.

In order that the cold air circulated in the closed cooling space 24 shall flow along a circuitous path therein, a plurality of partitions are so arranged in the jacket 22, as described hereinafter, that the air flows in countercurrent in each of the parts of the cooling space 24 situated respectively at the top, bottom, side walls and end walls of the outer casing. As shown, a horizontal partition 38 having the form of a rectangle, as viewed in plan, with part broken away, is situated substantially half way up the height of the inner chamber, and divides the closed cooling space 24 into substantially equal upper and lower portions, in which the air circulates in opposite directions. An end portion 40 of this partition terminates at the passageway 26, and a side portion 42 terminates at a situation spaced away from the end portion of the cooling space containing the cooling coil and fan, so that cold air returning towards the latter can flow downwards through the horizontal partition before continuing its path in the opposite direction below the horizontal partition.

A vertical partition 44, of U-shape, extends along the cooling space 24 at the top and bottom thereof, and has an end portion 46 that extends downwards to the top of the passageway 26, which vertical partition divides the closed cooling space 24 into two lateral portions which are in open connections one with the other at its end remote from the cooling coil and fan, because the upper and lower parts of the vertical partition 44 terminate respectively at 48 and 50 at situations spaced away from the adjacent end of the jacket.

Four slanting partitions 52, 54, 56 and 58 are arranged at the four corners of the cooling space. The two upper slanting partitions 54 and 56 and the upper part of the vertical partition 44 form two passages that extend completely along the top of the chamber, and are in open connection one with the other in the end of the jacket 22 remote from the cooling coil, and the lower slanting partitions 52 and 58 form with the lower part of the vertical partition 44 two passages which extend completely along the bottom of the inner chamber, and are also in open communication one with the other in the end of the jacket 22 remote from the cooling coil.

The described arrangement of the partitions, which provides for counter-current flow of the cooling air in various parts of the cooling space, promotes the thermal efficiency of the apparatus, and as the air in the closed cooling space 24 in the jacket 22 need not be changed when loading and unloading the chamber it can remain unchanged for very long periods, so that the efficiency of the apparatus is high. Moreover, it avoids the necessity for de-frosting the cooling coil 30, which would otherwise be necessary from time to time. Further as compared with known apparatus in which heat is permitted to leak through the outer casing by conduction or otherwise into the inner chamber and has subsequently to be cooled to the required temperature, the improved apparatus is more efficient because owing to the cooling space 24 in the jacket 22 being maintained always at a low temperature heat from the outer casing is prevented from gaining access to the air and goods in the inner storage chamber.

The invention is not restricted to the precise details enumerated above. For example, in some cases some other gas, such as carbon dioxide, may be circulated within the cooling space instead of air, and the word "air" used herein is intended to cover other gaseous cooling fluids besides atmospheric air where the context permits.

55 I claim:

1. A method of refrigeration comprising the steps of circulating cooling air in a cooling space extending around an inner cold storage chamber within an outer casing, and maintaining the same cooling air in the cooling space when opening and closing the inner chamber for loading and unloading purposes characterized by circulating the cooling air over substantially the entire area of each of the top, bottom, side, front and rear end walls of the inner chamber.

2. Refrigerating and cold storage apparatus comprising an outer casing having thermally insulated walls, an inner chamber for accommodating goods to be stored supported in the outer casing so as to form therein a sealed cooling space surrounding substantially the entire area of the top, bottom, side, front and rear end walls of the inner chamber, an air-tight cooling device and air-circulating means arranged in the sealed cooling space for circulating cold air

therein over all said walls of the inner chamber, and means enabling goods to be stowed in and removed from the inner chamber while retaining the cooling space sealed and thereby shut off from the atmosphere or from any other space.

3. Refrigerating and cold storage apparatus comprising a rectangular, thermically insulated, outer casing, a rectangular jacketed inner chamber therein for accommodating goods to be stored, the jacket of which inner chamber confines a sealed cooling space substantially completely surrounding all the walls of the inner chamber, an air-tight cooling device in the sealed cooling space, air-circulating means in the sealed cooling space, a plurality of partitions arranged to form in the cooling space a circuitous path in which the air-circulating means and the cooling device are situated, which path is so arranged that air circulated along it is adapted to flow in counter-current in each of the several parts of the cooling space situated respectively at the top wall, bottom wall, side walls and end walls of the jacket, a passageway for use in loading and unloading the inner chamber that extends air-tight through the sealed cooling space to the inner chamber, and opens at one end into the latter and at its other end through the outer casing, and closure means for closing the passage way.

4. Apparatus as set forth in claim 3, wherein a horizontal partition divides the sealed cooling space into substantially equal upper and lower portions, in which the cooling air is adapted to flow in opposite directions, which upper and lower portions are in open communication one with the other in a part of the sealed cooling space in which the cooling device and air-circulating means are situated, and a vertical partition divides the sealed cooling space into two

substantially equal lateral portions which are in open communication one with the other above and below the horizontal partition at a part of the sealed cooling space remote from the cooling device and air-circulating means.

5. Refrigerating and cold storage apparatus, comprising a thermically insulated, outer casing, a jacketed inner casing therein for accommodating goods to be stored, the jacket of which inner chamber confines a sealed cooling space substantially completely surrounding all the walls of the inner chamber, and is spaced away from the outer casing to form an air-space outside the jacket, an air-tight cooling device in the sealed cooling space, air-circulating means in the cooled sealing space, a passage-way for use in loading and unloading the inner chamber that extends air-tight through the air-space surrounding the jacket and through the sealed cooling space in the jacket to the inner chamber, and opens at one end into the latter and at its other end through the outer casing and closure means for closing the passage-way.
